FUEL INJECTION PUMP

Oscar G. Tweddell, Detroit, Mich.

Application December 20, 1935, Serial No. 55,322

3 Claims. (Cl. 103—41)

This invention relates to injectors for pumping fluids and particularly to an injector comprising several associated pumping mechanisms for producing a plurality of intermittent streams 5 of fluid in definite phase relationship with one another.

One of the objects of this invention is to provide an injector in which a plurality of pumping mechanisms are associated together and 10 driven by a common source of rotary power.

It is a further object of this invention to drive all of the associated pumping mechanisms with a single cylindrical cam, the form of which may easily be altered and adapted according to the 15 purpose for which the injector is to be used so that there may be produced any desired phase relationship between the several pumping mechanisms and consequently any desired phase relationship in the intermittent streams of fluid 20 produced by the several pumps.

Inasmuch as the injector herein disclosed is adaptable for use in internal combustion engines, it is a further object of this invention to provide each of the several pumps with a separate 25 by-pass valve and to provide means for simultaneously and uniformly regulating each of said valves so that each of said pumping mechanisms may be used to supply a uniformly regulated charge to one of the cylinders of such 30 engine.

It is a further object of the invention to construct such an injector in a simple and compact form to the end that manufacturing costs may be minimized and in a sturdy and rugged 35 form so that the serviceability of the injector may thereby be enhanced.

The above and other objects will appear more fully from the following detailed description accompanied by references to the drawing forming 40 a part hereof wherein is shown by way of illustration a satisfactory constructional example embodying the principles of the invention.

As shown in the drawing, Fig. 1 is a top view of the injector with a portion of the top broken 45 away so as to illustrate the actuation of the throttle mechanism;

Fig. 2 is a vertical, sectional view on an enlarged scale, taken along the lines 2—2 of Fig. 1 looking in the direction of the arrow;

50 Figs. 3 and 3a are fragmentary horizontal sectional views taken along the lines 3—3 of Fig. 2, showing the operation of the throttle mechanism in different positions;

Fig. 4 is a fragmentary horizontal sectional view taken along the lines 4—4 of Fig. 2; and

Fig. 5 is a fragmentary horizontal sectional view taken along the lines 5—5 of Fig. 2.

As shown in Fig. 2, the pumping mechanism is found within a cylindrical body 10 provided inwardly from the cylindrical surface thereof with six radially spaced pump chambers 11 of cylindrical cross section, which extend upwardly from the bottom of the body 10 and terminate in outlet holes 12 of reduced diameter. Ingress of fluid into each of the pump chambers 11 is had through inlet holes 13, which at circumferential intervals extend from the surface of the body 10 inwardly and communicate each with a corresponding pump chamber 11 at a point near the top thereof. The bottom of the cylindrical body 10 is provided with an axially centered cylindrical cam chamber 14 which is of such diameter as to intersect the pump chamber 11 at approximately the centers thereof and the depth of which is approximately half the height of the body 10. From the bottom of the cam chamber 14 an axially located bearing hole 15 extends upwardly to the top of the body 10, the lower part of said bearing hole 15 being somewhat counter-bored to form a step 17 suitable for the insertion of a journal 18.

A drive shaft 19 extends downwardly through the bearing hole 15 and journal 18 and terminates in a cylindrical cam 20 of dimensions adapted to fit within the cam chamber 14. A second drive shaft 21 of increased diameter extends downwardly from the bottom of the cylindrical cam 20.

Within each of the pump chambers 11 is positioned a piston 22 somewhat shorter in length than the pump chamber 11 and of such diameter as to fit nicely therein, the lower part of each of said pistons being of half moon section as at 24 so as to conform to the surface of the cylindrical cam 21 which extends into the pump chamber 11. For imparting to each piston 22 a reciprocating motion there is provided on its half moon face 24 a horizontally projecting roller 25 which engages a circumferential groove 26 in the surface of the cylindrical cam 20, said groove 26 being of rectangular section and in non-conformity with the radial plane of the cam 20. Means are provided for mounting the rollers 25 on the piston faces 24 and comprise, as shown in Fig. 5, short pins 25a at one end press fitted into the pistons 24 and carrying the rollers 25 on their projecting ends.

As shown in Fig. 2 the cylindrical body 10 with its associated mechanisms is surrounded by, and fits closely within, a casing 27 of generally an-

nular form. At the top of the casing 27 and bolted to it by suitable bolts 28 is a valve plate 29 of disk-like form, which, extending across the top of the body 10, is provided with a suitably disposed central aperture 31 through which projects the aforementioned shaft 19. A flanged supporting piece 32 is likewise bolted to the bottom of the casing 27, the shaft 21 extending downwardly through a journal 33 frictionally mounted in the flanged supporting piece 32. In order to accommodate the thrust resulting from the action of the cylindrical cam 20 the upper part of the journal 33 is provided with a flanged portion 34 which bears against the lower part of the cam 20.

Within the casing 27 is located an annular fluid chamber 36 which may be suitably connected to the fluid reservoir (not shown). Appropriate channeling for conveying fluid from the fluid chamber 36 to each of the pump chambers 11 is supplied by circumferentially spaced apertures 37 extending upwardly from the fluid chamber 36, each of which apertures communicates with a deep groove 38 in the top surface of the casing 27, each groove 38 extending radially inwardly to communicate with the respective outlet hole 12 associated with the corresponding pump chamber 11. Each of the apertures 37 is provided with a ball check valve 39 which seats on the top of said aperture at its intersection with the associated groove 38, the seating force being derived from the pressure of a spiral spring 41 located within a suitably disposed spring chamber 42 extending upwardly within the valve plate 29.

For controlling the escape of fluid from the pump chambers 11 each of the outlet holes 12 is provided with a ball check valve 43 and spiral spring 45, both operating within a suitably aligned upwardly extending cylindrical valve chamber 44 located within the valve plate 29. Near the top and at the outside edge of each of the valve chambers 44 an outlet passage 46 of reduced diameter extends upwardly to the top surface of the valve plate 29 for conveying to the throttle mechanism to be described, the liquid passed by the ball check valve 43.

In order to regulate and limit the pressure which may be developed by the individual pumps, each of the same is furnished with a by-passing mechanism which comprises, as shown most clearly in Fig. 1, a plurality of angularly spaced by-passing conduits 47 each associated with one of the cylindrical holes 44 and extending horizontally outwardly therefrom to the edge of valve plate 29, each of said holes being counterbored to form valve chambers 48, ball check valves 50 seating on the shoulders 49 formed by the counterboring. Hollowed plugs 51, each threaded into the outer end of a valve chamber 48 and locked in position by a lock nut 52, contain spiral springs 53 which urge the ball check valves 50 into seated position. Return flow conduits 64 extend downwardly from the valve chambers 48 through the bottom of the valve plate 29 and the upper portion of the casing 27 to communicate with the liquid reservoir, thus providing a drainage for liquid passed by the ball check valve 50. To provide a return flow for the throttling mechanism, subsequently to be described, each of the valve chambers 48 is provided at its inner end with throttle return conduit 54 extending upwardly to the top surface of valve plate 29.

Means for throttling the output from each of the associated pumps comprise a throttle plate 55 mounted on the top of the valve plate 29 and centrally apertured at 56 to allow the passage

therethrough of the shaft 19 and surrounding journal 57. The throttle plate 55 is encased within a cover plate 58 provided with a circular flange 59 extending downwardly around the edge of the throttle plate 55 to rest upon the top of valve plate 29. A central aperture 60 in the cover plate 58 allows the passage therethrough of shaft 19 and journal 57.

As shown in Fig. 2, the top of the cover plate 58 is provided with a plurality of delivery orifices 61, each located in alignment with one of the outlet passages 46. Communication between each of the delivery orifices 61 and its corresponding outlet passage 46 takes place through a slot 66 extending through the throttle plate 55, the slots 66 being arced so as to remain at all times in proper registration. The throttling action of the throttle plate 55 is obtained by the action of grooves 67 in the bottom of the throttle plate 55. As shown in Figs. 3 and 3a, each of said grooves 67 is associated with one of the slots 66 and extends from one end thereof tangentially outwardly towards the edge of the throttle plate 55. By rotating the throttle plate 55 the outer end of each of the grooves 67 may be brought into or out of registration with the corresponding aforementioned throttle return conduit 54.

Means are provided for actuating the throttle plate 55 and controlling the angular position thereof and comprise a rack 68 operating in a horizontally directed hole 71 in one side of the cover plate 58 and engaging a toothed section 70 in the edge of the throttle plate 55. A stop rod 72 extending forwardly from the end of the rack 68 is provided at its end with a locked pair of nuts 73 which by their engagement with the surface of the cover plate 58 limit the movement of the rack 68.

Depending upon the use to which the injector may be devoted, the delivery orifices 61 may be joined together to a common delivery tube (not shown) or each delivery orifice 61 may be connected to a distinct delivery tube as will be the case where the purpose is to furnish fluid to a cylinder of an internal combustion engine. Likewise, the shaft of cam 26 is subject to change both in the number of throws per turn and the character of the throws so as to suit the particular application at hand.

The operation of the device is as follows:

Rotation of the drive shaft 21 and the cam 20 mounted thereon causes the pistons 22 to reciprocate by reason of the engagement of rollers 25 with the slot 26 in the surface of cam 20. The reciprocating motion of the pistons 22 draws liquid from the liquid chamber 36 and pumps the same into the respective valve chambers 44, the ball check valves 39 and 43 functioning in a manner well understood.

Depending upon the adjustment of the plugs 51 and the stiffness of the springs 53, a portion of the liquid thus pumped may be shunted past valves 50 and downwardly through conduit 64 into the fluid reservoir 36.

That part of the liquid not passed by the valves 50 is forced upwardly through the conduits 46 and into slots 66 in the throttle plate 55. If the throttle plate is positioned as shown in Fig. 3, with the grooves 67 in full registration with the throttle return conduits 54, substantially all of the liquid will escape through the grooves 67 and conduits 54 and return downwardly to the liquid reservoir 36.

On the other hand, if, as shown in Fig. 3a, the grooves 67 are but in partial registration with the

conducts 54, only a portion of the liquid pumped will so escape and the remainder will be delivered through the respective outlets 61. Likewise, the throttle plate 55 may be adjusted so that there 5 is no registration, in which case all the liquid will be delivered to the outlets 61.

As appears from the foregoing description, the amount of liquid delivered is subject to accurate control, rack 69 serving to regulate the position 10 of throttle plate 55. Inasmuch as the grooves 67 extend not radially but tangentially, the ratio of change of angular position of the throttle plate to change of registration of the grooves 67 with the conduits 54 is relatively great, and lends precision to the action of the throttle plate 55. The provision of stop bolts 73 prevents the rotation of the throttle plate 55 beyond the position of full registration.

Although there has been described but one 20 specific embodiment of the invention, it will be understood by those familiar in the art, that numerous changes and alterations may be made in the invention disclosed without departing from the spirit and scope thereof commensurate with 25 the appended claims.

I claim:

1. An injector comprising a plurality of pumps actuated by a common source of power, each of 30 said pumps being operatively connected to a fluid source and provided with a separate outlet passage, a valve plate provided with a plurality of return flow conduits communicating with said fluid source and intersecting the surface of said valve plate at points uniformly distant from the 35 center of said valve plate, a throttle plate positioned on the surface of said valve plate and rotatable about an axis coincident with the center of said valve plate, said throttle plate being provided with throttling passages each communicating 40 continuously with one of said outlet passages, said throttling passages in one position of said throttle plate each being in registration with one of said return flow conduits, and means for rotating said throttle plate so as partially or 45 wholly to destroy the registration between said throttling passages and said return flow conduits.

2. An injector comprising a plurality of pumps actuated by a common source of power, each of 50 said pumps being operatively connected to a fluid source and provided with a separate outlet passage, a valve plate provided with a plurality of re-

turn flow conduits communicating with said fluid source and intersecting the surface of said valve plate at points uniformly distant from the center of said valve plate, a throttle plate positioned on the surface of said valve plate and rotatable about 5 an axis coincident with the center of said valve plate, said throttle plate being provided with throttling passages each communicating continuously with one of said outlet passages, said throttling passages in one position of said throttle plate 10 each being in registration with one of said return flow conduits, and means for rotating said throttle plate so as partially or wholly to destroy the registration between said throttling passages and said return flow conduits, said means comprising 15 a plurality of gear teeth on the periphery of said valve plate and a manually operable member for engaging said teeth to adjust said throttle plate.

3. In a device of the character described, a main substantially cylindrical housing, a plurality 20 of cylinders formed therein and concentrically spaced about the axis of said housing, a plurality of pistons, each slidably mounted in one of said cylinders, a valve plate abutting said housing at the delivery end thereof, a valve cover plate abutting said valve plate and having a cylindrical recess in its under surface and having for each of said cylinders a discharge conduit communicating with said recess, said valve plate having for each of said cylinders an outlet conduit furnishing communication from said cylinders to said recess, exhaust valves, one in each of said outlet conduits, said valve plate having for each of said cylinders a relief conduit communicating with said outlet conduit on the exhaust side of the 35 exhaust valve therein contained, relief valves, one in each of said relief conduits, a throttle plate mounted for rotation in said cylindrical recess, and having for each of said cylinders a slot formed to remain in registry with one of said 40 outlet conduits and one of said discharge conduits upon rotation of said throttle plate, said valve plate having for each of said cylinders a by-pass conduit communicating with said recess and each of said slots having a by-pass extension registerable with one of said by-pass conduits upon rotation of said throttle plate, and means for securing said valve plate and said cover plate to said 45 housing.

OSCAR G. TWEDDELL. 50
